(57) **CLAIM**

The ornamental design for a dessert loaf enclosure, as shown and described.

DESCRIPTION

FIG. 1 is a perspective view of a dessert loaf enclosure according to a preferred embodiment.

FIG. 2 is a front view of a dessert loaf enclosure according to the embodiment of FIG. 1.

FIG. 3 is a side view of a dessert loaf enclosure according to the embodiment of FIG. 1.

FIG. 4 is a perspective view of a dessert loaf enclosure according to another embodiment.

FIG. 5 is a front view of a dessert loaf enclosure according to the embodiment of FIG. 4.

FIG. 6 is a side view of a dessert loaf enclosure according to the embodiment of FIG. 4.

FIG. 7 is a perspective view of a dessert loaf enclosure according to another preferred embodiment.

FIG. 8 is a front view of a dessert loaf enclosure according to the embodiment of FIG. 7.

FIG. 9 is a side view of a dessert loaf enclosure according to the embodiment of FIG. 7.

FIG. 10 is a perspective view of a dessert loaf enclosure according to another preferred embodiment.

FIG. 11 is a front view of a dessert loaf enclosure according to the embodiment of FIG. 10.

FIG. 12 is a side view of a dessert loaf enclosure according to the embodiment of FIG. 10.

FIG. 13 is a perspective view of a dessert loaf enclosure according to another embodiment.

FIG. 14 is a front view of a dessert loaf enclosure according to the embodiment of FIG. 13.

FIG. 15 is a side view of a dessert loaf enclosure according to the embodiment of FIG. 13.

FIG. 16 is a perspective view of a dessert loaf enclosure according to another preferred embodiment;

FIG. 17 is a front view of a dessert loaf enclosure according to the embodiment of FIG. 16; and,

FIG. 18 is a side view of a dessert loaf enclosure according to the embodiment of FIG. 16.

The oblique line shading in FIGS. 1-9 is used to depict transparent or translucent materials. The broken lines shown in the drawings are for illustrative purposes only.
